UNITED STATES PATENT OFFICE.

JOHN A. MAKARHOF, OF CHICAGO, ILLINOIS, ASSIGNOR, BY DIRECT AND MESNE ASSIGNMENTS, OF FORTY-NINE ONE-HUNDREDTHS TO F. R. BELT AND FIFTY-ONE ONE-HUNDREDTHS TO GEORGE A. BAIRD, BOTH OF CHICAGO, ILLINOIS.

SAFETY-RAZOR.

1,016,344.

Specification of Letters Patent.

Patented Feb. 6, 1912.

Application filed April 20, 1911. Serial No. 622,203.

To all whom it may concern:

Be it known that I, JOHN A. MAKARHOF, a citizen of the United States, residing at Chicago, in the county of Cook and State 5 of Illinois, have invented certain new and useful Improvements in Safety-Razors, of which the following is a specification.

This invention relates to safety razors and aims to produce a device of this character 10 which shall be simple in construction, cheap to manufacture, which shall be strong and durable and which will hold the blade firmly in cutting position so that no vibration of the blade on its holder will take place when 15 the device is being used.

The following description when read in connection with the accompanying drawings illustrating one preferred form of my 20 invention, will be sufficient for an understanding of the structure, the mode of operation and many of the desirable features thereof.

Referring to the drawings: Figure 1 is a sectional elevation taken on the line 1—1 of 25 Fig. 2; Fig. 2 is a plan view; and Fig. 3 is a rear view of a razor embodying my invention; and Fig. 4 is a detail perspective view of the base member of the device.

On the drawings, 5 designates the base 30 member which has a flat upper surface, the forward end of the member being upturned to form the guard 6 and being provided with a transversely extending slot 7 through which the cutting edge of the blade 8 disposed on the flat face of the base member, projects. The bottom of the base member is preferably curved upwardly near its forward end to permit the cutting edge of the blade to be disposed at the proper angle and 35 the rear edge of the member is preferably cut away as indicated at 9 to enable the rear edge of the blade to be grasped by the fingers and removed from operative position. Suitable studs or lugs 10 project upwardly from the rear edge of the member 40 behind the blade to prevent the blade from sliding backward on the member and the ends of the groove 7 are preferably inclined as indicated at 11 to coöperate with the 45 similarly inclined forward corners of the blade to prevent the cutting edge thereof from projecting too far through the slot. 50

The sides of the base member are provided with upstanding ears or projections

12 perforated to receive a bearing pin or 55 rod 13 upon which is pivotally mounted a cam 14. A handle 15, preferably constructed integrally with the cam, provides a means whereby the cam may be turned on its pivot to bring its face into engagement 60 with the upper face of the blade to clamp the blade in position between the base member and the cam. It will be evident that when the handle is turned backwardly or to the left, viewing Fig. 1, the cam will be released from engagement with the blade to permit the blade to be lifted out over the lugs 10 and withdrawn for the purposes of sharpening or cleaning the same.

In order that the blade may be tightly 70 clamped and held adjacent its cutting edges to prevent the blade from vibrating on the base member when the device is being used, I have provided a locking shoulder 16 preferably integrally constructed with the cam 75 and with the handle and adapted when the cam is forced into locking position, as shown in Fig. 1, to engage the blade adjacent its cutting edge and clamp the same firmly against the base member. By this construction the blade is clamped and tightly held throughout its length by the cam 14 and is furthermore clamped and held against vibration adjacent its cutting edge by the locking shoulder 16. When the handle is 80 moved into the position shown in Fig. 1, to lock the blade on the base member, the razor is ready to be used, when it is desired to remove the blade or to insert a new one, the handle is simply turned backwardly to release the cam and the locking shoulder from engagement with the blade whereupon the blade can be readily removed and another inserted in its stead.

It will here be explained that the base 95 member 5 together with the upstanding ears 12 constitute a seat for the reception of the blade, the upper side of the seat being open so as to permit of the periphery of the cam 14 working through said open side of the 100 seat into engagement with the blade so as to press the latter against the back of the seat.

It is believed that the invention and many of its advantageous features will be understood from the foregoing without further description and it will be obvious that various minor mechanical changes in the size, 105

shape, proportion and arrangement of the various parts may be resorted to without departing from the spirit of the invention or sacrificing any of the material advantages thereof.

I claim:

1. A safety razor comprising a base member provided with a seat having one side open, a rotatable cam mounted upon the 10 base member between the front and rear thereof and extending from side to side of the base member with its axis disposed parallel to the cutting edge of the razor blade, the periphery of the cam working 15 through the open side of the seat in position to engage the blade and press the same against the back of the seat, and a handle for manipulating the device carried by the cam, substantially as described.
2. A safety razor comprising a base member provided with a seat having an open side, a guard extending across the front of the seat, ears upon the body at opposite sides of the seat, a cylindrical clamping 25 member having its axis disposed in substantial parallelism with the guard and its ends eccentrically mounted in the ears, the periphery of the clamping member working through the open side of the seat in position 30 to press a blade and hold the same against the back of the seat, and a handle for manipulating the device carried by the clamping member, substantially as described.
3. A safety razor comprising a base member provided with a seat having one side open, a rotatable cam mounted upon the 35 base member between the front and rear thereof and extending from side to side of the base member with its axis disposed parallel to the cutting edge of the razor blade, the periphery of the cam working 40 through the open side of the seat in position to engage the blade and press the same against the back of the seat, a handle for manipulating the device carried by the cam, and a brace member movable with the clamp- 45 ing member, substantially as described.

ing member and disposed in position to lie against the blade between the clamping member and the cutting edge of the blade to 50 prevent vibration of said cutting edge, substantially as described.

4. A safety razor comprising a base member provided with a seat having an open side, a guard extending across the front of 55 the seat, ears upon the body at opposite sides of the seat, a cylindrical clamping member having its axis disposed in substantial parallelism with the guard and its ends eccentrically mounted in the ears, the periphery of 60 the clamping member working through the open side of the seat in position to press a blade and hold the same against the back of the seat, a handle for manipulating the device carried by the clamping member, and 65 a brace member movable with the clamping member and disposed in position to lie against the blade between the clamping member and the cutting edge of the blade to prevent vibration of said cutting edge, 70 substantially as described.

5. A safety razor comprising a base member provided with a seat having an open side, a guard extending across the front of the seat, a rotatable cam mounted upon the 75 base member between the front and rear thereof and extending from side to side of the base member with its axis disposed substantially parallel with the guard, the periphery of the cam working through the 80 open side of the seat in position to engage a blade and press the same against the back of the seat, and a handle for manipulating the razor carried by the cam, said handle being disposed at an acute angle 85 with respect to the forward portion of the base member and extending in front of the guard in the clamped position of the handle, substantially as described.

JOHN A. MAKARHOF.
